UNITED STATES PATENT OFFICE.

LEO G. SHARYON, OF LITTLE FALLS, MINNESOTA.

PAPER-CUSPIDOR HOLDER.

1,388,771.

Specification of Letters Patent. Patented Aug. 23, 1921.

Application filed July 3, 1919. Serial No. 308,444.

To all whom it may concern:

Be it known that I, LEO G. SHARYON, a citizen of the United States, residing at Little Falls, in the county of Morrison and 5 State of Minnesota, have invented certain new and useful Improvements in a Paper-Cuspidor Holder, of which the following is a specification.

In factories and other buildings employing a large number of workers it frequently occurs that, for sanitary reasons, cuspidors constructed of paper are used so that when once used they may be discarded. However, owing to the characteristic weakness of 10 paper and like materials the cuspidors are easily and frequently crushed and thus rendered useless and unsanitary.

It is the object of the present invention to provide a simple and efficient holder for cuspidors of this character which is constructed of metal or other material having a requisite degree of strength and rigidity to withstand the rough treatment to which it is subjected during use and thus maintain the cuspidor in proper shape.

Another object is the provision of a holder of this character which facilitates quick and convenient removal of the cuspidor therefrom, when necessary.

30 In the accompanying drawings:

Figure 1 represents a top plan of the holder,

Fig. 2 represents a broken sectional view on the line 2—2 of Fig. 1, and

35 Fig. 3 represents a similar sectional view of a modified type of holder.

Referring to the drawing in detail, wherein similar reference numerals designate corresponding parts throughout the several 40 views the numeral 5 indicates a conventional type of paper cuspidor, which as usual consists in the four upwardly and outwardly inclined side walls and the imperforate bottom 6.

45 The improved holder consists of a circular body 5^a preferably constructed of sheet metal and of adequate height to support the imperforate bottom 6 of the paper cuspidor in elevated position with relation to the floor or other object upon which the holder 5^a is arranged. The lower edge of the circular body 5^a is turned outwardly and upwardly

as at 6^a in order that the cuspidor may be easily moved across the floor or other support and the turned edge provides a circular channel for receiving and retaining such liquid as may be accidentally directed against the circular body 5^a. The upper edge of the circular body is formed with four equidistant V-shaped recesses 7 in 60 which the corners of the paper cuspidor 5 are received, thus supporting the cuspidor in elevated position and preventing it from turning within the holder.

Referring to Fig. 3 of the drawing where-in a modification of the improved holder is illustrated the numeral 10 indicates the circular body of the holder provided with the outturned bottom edge 11 and having four groups or pairs of slits 12 extending downwardly from the top edge thereof. The material lying between the slits of each group is directed downwardly and inwardly as at 13 providing a support for the bottom of the cuspidor, the corner portions of which project through the spaces between the slits 12 and thus prevent accidental turning of the cuspidor within the holder.

From the foregoing, it is evident that both types of holders will effectively protect the 80 paper cuspidor against crumpling or other injury thereto incident to being struck when in use.

Although the recesses in the sides of the cuspidor holders are especially provided for 85 the reception of the corners of rectangular or polygonal paper cuspidors it will be readily appreciated that the device may be utilized with equal efficiency in receiving and supporting cuspidors of circular form and 90 therefore I do not desire to be limited as to the particular type of paper cuspidor to be used in connection with my invention.

What I claim is:

1. A holder for paper cuspidors of rectangular form comprising a circular body member adapted to receive a cuspidor, downwardly and inwardly directed supporting members struck from the top edge of the body member to engage beneath the bottom 100 wall of the cuspidor, the struckout portions of the body forming a plurality of recesses in the top edge thereof adapted to accommodate the corners of the cuspidor to prevent

accidental displacement of the latter relative to the holder.

2. A holder for paper cupidors of rectangular form, comprising a circular body member adapted to receive a cupidor, the vertical portion of said body member having a plurality of struck-out portions whereby

to form recesses adapted to accommodate the corners of the cupidor to prevent accidental displacement of the latter relative to the holder. 10

In testimony whereof, I affix my signature hereto.

LEO G. SHARYON.
